UNITED STATES PATENT OFFICE

2,574,002

WEB HANDLING MECHANISM FOR MULTI-COLOR PRINTING PRESSES

Adolph Weiss, Brooklyn, N. Y., assignor to Inter-chemical Corporation, New York, N. Y., a corporation of Ohio

Application December 3, 1945, Serial No. 632,412

11 Claims. (Cl. 101—181)

1

This invention relates primarily to a press for printing designs in combinations of colors upon webs of textile material. The securement of registration of colors upon a textile web presents a problem of particular difficulty not ordinarily encountered in printing upon paper, because the textile web can be so easily stretched or distorted. This is particularly true because stretching of the web lengthwise tends to narrow the web widthwise, and thus disturbs lateral as well as longitudinal registration.

In the patent to Wickwire #2,240,249, granted April 29, 1941, the problem of controlling the tension of the web throughout printing is solved by providing a succession of printing couples each comprising a printing cylinder and a coacting impression cylinder, and by further providing web transfer drums between successive impression cylinders and in bearing relation to the adjacent impression cylinders, so that from the point where the web first reaches the printing mechanism to the point where the web finally leaves the printing mechanism, the web is continuously in engagement with the surface either of an impression cylinder or of a web transfer drum, there being no gap or space in which the web runs free or is dragged over a stationary surface. The web transfer drums run at the same surface speed as the impression cylinders and the printing cylinders. This principle is adhered to in the illustrative machine of the present application.

The present invention is, in general, directed to improvements in machines of the Wickwire type, although certain features of the invention are of broader scope and utility.

In the printing of textiles, different form lengths are used for different jobs, and hence printing or engraving cylinders of different diameters are required to be used on different jobs.

It is an important object of the present invention to provide for the rapid and efficient temporary withdrawal of the impression cylinders together with the associated web transfer drums to permit replacement of the printing cylinders, and for the rapid and efficient restoration of the impression cylinders and the web transfer drums in properly coacting relation to one another and to the printing cylinders, whether the replacement printing cylinders be of the same size as those replaced or of a different size.

To this end, it is an important feature of the invention that each impression cylinder is paired with one of the associated web transfer drums to form an adjustable unit, a common adjustable support and operating means therefor being pro-

2

vided for each associated pair to carry such pair as a unit toward and from operative position.

It is a further object of the invention to mount and control the web transfer drums in such fashion that each drum may be caused to bear with a nicely determined pressure against the associated or paired impression cylinder, and also against the neighboring impression cylinder with which it cooperates, in order that proper pressures may be secured and maintained in every instance appropriate to the thickness and character of any textile material upon which it may be desired to print.

For this purpose it is a feature that each carrier drum is slidably mounted with capacity for movement toward and from the axis of the associated impression cylinder and is urged with adjustable spring pressure toward such impression cylinder. It is a further feature that each carrier drum which coacts with more than one impression cylinder is mounted with capacity for rocking movement relative to the support by which it is carried in common with its associated impression cylinder, to rock toward and from a neighboring impression cylinder, and is urged with adjustable spring pressure toward such neighboring impression cylinder.

A further object of the invention is to relieve the textile web of strain and rubbing incidental to the driving of the ponderous carrier drums from the impression cylinders. Each impression cylinder is frictionally driven from the associated printing cylinder, and, in turn, is caused to drive the associated carrier drum, both the cylinders and the drum traveling at the same surface speed.

The driving of the carrier drum is not, however, effected exclusively by friction through the textile web, but the driving is very materially assisted and principally effected through a V-belt slip drive which may be adjusted as to driving ratio, so that it will tend to drive the carrier drum at the same surface speed as the associated impression cylinder. This auxiliary drive is advantageous because it obviates the need for driving pressure upon the web between the impression cylinder and the carrier drum, and thereby avoids spreading and smearing of the applied colors.

It is a further object of the invention to provide a cleaning unit in association with each carrier drum which runs in engagement with a printed portion of the web, driven from the associated impression cylinder and by the same means through which the drive is transmitted from the impression cylinder to the associated carrier drum.

Other objects and advantages will hereinafter appear.

In the drawing forming part of this specification

Fig. 1 is a diagrammatic view in front elevation of a machine embodying the invention;

Fig. 2 is a central, transverse, vertical, sectional view of a portion of the machine illustrated in Fig. 1;

Fig. 3 is a fragmentary view in front elevation of a portion of the mechanism illustrated in Fig. 2, the view being on a larger scale than Fig. 2;

Fig. 22 is a plan view showing an ink reservoir unit in association with an engraving cylinder; and

Fig. 23 is a view in front elevation of the structure shown in Fig. 22.

Before going into detail, the general organization and principle of the illustrative machine will be first briefly described in outline form by reference to the diagrammatic showing of Fig. 1 and limited reference to Fig. 2.

A web 1 of textile fabric or other suitable material to be printed is drawn off a web supply reel 2 by a driven feed couple, comprising opposed rollers 3 and 4, at as nearly as practicable the same speed at which it is to pass through the printing instrumentalities of the press. The web passes from the feed couple 3-4 beneath a monkey roll 5 which is carried by a pivoted arm 6, and over a breaker roll 7 to the printing mechanism.

The printing mechanism is illustrated as comprising three printing couples, although any desired number of such couples may be provided. The web 1 travels first around a guide cylinder 1x to a first web carrier drum 8, and thence around an impression cylinder 9 past an engraving or printing cylinder 10 by which the first color is applied. Upon leaving the first impression cylinder, the web 1 travels around a second transfer drum 8a, then around a second impression cylinder 9a past a second engraving cylinder 10a by which the second color is applied. Similarly, upon leaving the second impression cylinder, the web 1 travels around a third transfer drum 8b, then around a third impression cylinder 9b past a third engraving cylinder 10b by which the third color is applied. After leaving the third impression cylinder, assuming in consonance with the illustration that application of three colors is desired, the web is desirably caused to travel beneath a guide roll 11 and onto a web rewind reel 12.

The web transfer drums 8-8b complement the impression cylinders 9-9b to provide moving surfaces traveling uninterruptedly in engagement with the web from a point in advance of the first printing operation to a point following the last printing operation, to avoid changes in tension of the web and to keep the web evenly and smoothly spread out. The engraving cylinders 10-10b are uniformly driven at the same speed and act through the web frictionally to drive the impression cylinders 9-9b, respectively, at the same speed with themselves. The impression cylinders 9-9b, in turn, drive the web transfer cylinders 8-8b at the same speed at which the engraving and impression cylinders travel.

Referring now to Fig. 2, the printing mechanism consists substantially of a succession of printing units through which the web passes successively and continuously. These units are alike and are all carried by front and rear frame members 13 and 14. The parts of the first unit will be described in detail, and no detailed description of the second and third units will be given, but corresponding reference numerals will be applied to corresponding parts of the second and third printing units with the subscripts "a" and "b" added, respectively, in each instance.

The first unit, in addition to the web transfer drum 8, the impression cylinder 9, and the engraving cylinder 10 includes an ink reservoir 15 and a driven ink applying roller 16 which runs in engagement with the engraving cylinder 10. The reservoir 15 with its ink applying roller 16 is removable from the machine. The engraving cylinder may also be removed to permit replacement when the reservoir is not present.

Engraving cylinders of different diameters are

employed for different jobs, but the frame members 13 and 14 provide bearing for the engraving cylinders in just one fixed axial position. It is important, therefore, that practical means be provided for conveniently mounting the impression cylinders in different operative positions and for operating them to different operative positions, suitable for cooperation with engraving cylinders of different diameters. Since the transfer drums run in bearing relation to the impression cylinders, it is necessary that provision be made for adjustable operation of the transfer drums also, and this is desirably achieved in accordance with the present invention by making each transfer drum adjustably operable in unison with the impression cylinder of the corresponding printing unit.

By reference particularly to Figs. 7 and 8, it will be observed that the impression cylinder 9 is mounted in roller bearings 21 carried by complementary casing members 22 and 23 which form parts of a slide structure 24. Each housing member 23 has formed integrally with it a slide extension 25, which travels in guideways 26 formed in one or the other of the frame members 13, 14. Upper and lower guide plates 27 and 28 are fixed to the frame member and cooperate with the frame structure for embracing and guiding each slide block 25. The guideways of the frame members 13 and 14 extend in parallelism with one another, and in a direction to guide the impression cylinder 9 directly toward and from the cooperative engraving cylinder 10, this direction being desirably a horizontal direction.

As an advantageous means for operating the slides 25 in opposite directions, each slide is provided with a screw 29 which extends rearward through a threaded sleeve 30. The sleeve 30 is held against axial movement and is made fast with a worm wheel 31 which is adapted to be driven by a worm 32 fast upon a shaft 33. The gear 31 is desirably mounted in ball bearing 34 carried between end plates 35 of a housing bracket 36. The shaft 33 is connected to be rotated in either of two opposite directions by a reversible electric motor (not shown) and is equipped with two worms for driving the respective worm gears 31 at opposite ends of the impression cylinder 9 in unison with one another. A thrust ball bearing 37 (see Fig. 7) is carried by each of the housing brackets 36 for resisting endwise movement of the sleeve 30 and for permitting free rotation thereof.

It will be seen that the slides 25 are advanced and retracted in unison, and hence that the impression cylinder 9 is advanced and retracted without disturbing the parallel relation of the impression cylinder axis to the engraving cylinder axis.

The complementary housing members 22 and 23 of each of the housing members 24 are formed to provide a bearing 38 for receiving a pivot stud 39 (see Fig. 5). The studs 39 are in axial alignment with one another and extend parallel to the axis of the impression cylinder 9, each stud providing a journal for a rocker arm 40. The rocker arms 40 jointly constitute a swing frame in which the web transfer drum 8 is carried.

As best seen in Figs. 3 and 4, each rocker arm comprises side members 42 and 43 which are connected to one another through a head member 44. The side members 42 and 43 are formed with guide flanges 45 and 46 which extend inward toward one another. The shaft 47

of transfer drum 8 is supported at its opposite ends in bearings 48 which are carried in complementary housing members 49 and 50. The housing members 49 and 50 are formed with side channeled portions for embracing, respectively, the guide flanges 45 and 46, so that the bearings for the shaft 47 of web transfer drum 8 are mounted with capacity for sliding movement toward and from the impression cylinder 9.

Provision is made for urging the web transfer drum 8 toward the impression cylinder 9 along the guides 45 and 46 with adjustable spring pressure. A headed and externally threaded sleeve 51 is screwed through the head member 44 and bears through a washer 52 against one end of a compression coil spring 53. The other end of the spring 53 bears against the upper end of the housing formed jointly by the members 49 and 50, urging the housing away from the sleeve 51. A guide stem 54 extends through the spring 53 and has reduced lower and upper end portions 55 and 56, the latter of which is threaded. A collar 57 is inserted in a slot formed in the upper portion of the housing formed jointly by the members 49 and 50, and is impaled upon and pinned to the reduced lower end 55 of the stem 54, so that the head portion of the housing formed jointly by the members 49 and 50 is fixed relative to the stem between a shoulder of the stem which engages the upper face of the housing and the collar 57. The large portion of the stem 54 is slidable in a bore 58 formed in the lower end of the sleeve 51, and the upper reduced threaded end portion 56 of the stem 54 passes freely through the sleeve 51. A pair of nuts 59 and 60 is threaded upon the reduced upper end 56 of stem 54, the nut 59 serving as a limit stop and the nut 60 serving as a lock nut for the nut 59. The nut 59 is normally out of engagement with the sleeve 51 when the web transfer cylinder 8 bears against the impression cylinder 9.

The limit nut 59, however, performs an important function in the assembly of the machine since it enables the swing frame and the transfer drum to be put in place as an assembled unit with the transfer drum 8 out of engagement with the cylinder 9. After the swing frame and transfer drum have been put in place, adjustments are made for causing the transfer drum 8 to bear against the impression cylinder 9 with the desired pressure.

The limit nut 9 also serves in cooperation with the threaded sleeve 51 to enable the transfer drum 8 to be withdrawn from engagement with the impression cylinder 9 by rotation of the sleeve 51 for facilitating the threading of the web through the machine.

The web transfer drum 8 does not bear against any impression cylinder above it as do the transfer drums 8a and 8b. In order that the parts may be of uniform construction and interchangeable, the mounting means for the transfer drum 8 is, nevertheless, made the same as that for the transfer drums 8a and 8b.

Each of the rocker arms 40 has pivotally connected to it through a pivot pin 71, a link 72 which includes a threaded stem 73. The stem portion 73 extends freely through a threaded and headed sleeve 74 which is screwed into a fixed frame member 75. A compression coil spring 76 surrounds the stem portion 73 of the cylinder 72 and bears at its opposite ends against a shoulder of the link 72 and against an end face of the threaded sleeve 74. A limit nut 77 is threaded

on the lower end of the stem 13 and a lock nut 18 is also threaded on the lower end of the stem to lock the limit nut 11 in position.

As viewed in Fig. 3, the tendency of the spring 16 is to urge the link 12 upward, and thereby to swing the rocker arm 40 and the transfer drum 8 in a counterclockwise direction about the pivot of the rocker arm. In the case of the transfer drum such as 8a and 8b, which engage two impression cylinders, this rocking movement is limited by the upper of the two impression cylinders which the transfer drum engages. This pressure may be increased by turning the sleeve 74 to raise the sleeve, and thereby put the spring 16 under greater compression, and may be reduced by turning the sleeve 74 in a direction to lower the sleeve.

In the case of the upper transfer drum 8 where there is no upper impression cylinder for the drum 8 to engage, the limit nut 11 is adjusted to arrest counterclockwise rocking of the rocker arm 40 in a desired position.

The limit nut 11 may be employed in the case of the transfer drums 8a and 8b, in cooperation with the sleeve 74, for rocking the transfer drum out of engagement with the upper engaged impression cylinder to facilitate threading of the web through the machine.

The rocker arms 40 are connected rigidly to one another to complete the swing frame through a cleaning reservoir unit 79. The reservoir includes mounting brackets 80 which are rigidly attached through screws 81 to the rocker arms 40. The structure of the reservoir unit (see particularly Fig. 9) comprises a main casing member 82, end plates 83 and 84, and end caps 85 and 86. The members 82, 83 and 84 jointly define the reservoir in which a supply of cleaning fluid is maintained.

Upper and lower rollers 87 and 88 are carried within the reservoir, being mounted, respectively, upon shafts 89 and 90 which are mounted in bearings carried by the end members 83 and 84 and the caps 85 and 86. The roller 87 runs in engagement with the transfer drum in the same rotatory direction as the transfer drum, so that it has rubbing engagement with the transfer drum. The drive shaft 89 of the roller 87 has affixed to one end thereof a drive pulley 91. Drive gears 92 and 93 of equal diameters are fast, respectively, upon the shafts 89 and 90 and mesh with one another for driving the roller 88 at the same speed as the roller 87 in the opposite direction of rotation from the roller 87. The roller 88 runs in the cleaning fluid contained in the reservoir and transfers it to the roller 87 for application by the latter roller to the surface of the transfer drum.

In the case of the first transfer drum 8 no cleaning unit is necessary for the reason that the transfer drum 8 never runs in engagement with a portion of the web to which printing has been applied. The cleaning units are required for transfer drums 8a and 8b, and a pulley corresponding to 91 with a suitable mounting must at least be provided in connection with the transfer drum 8, as will be apparent from the description of the driving means near the transfer drum which will presently be given.

The end members 83 and 84 are joined through a tie rod 94 upon which a combined cover and doctor blade carrier 95 is pivotally mounted. The doctor blade 96 is clamped in adjusted position between the cover 95 and a clamping plate 97 by means of headed screws which pass through

7 the clamping plate 97 and through slots in the doctor blade, and are threaded into the cover 95.

Arms 98 affixed to the cover 95 extend downward across the upper margin of the casing member 82, and adjusting screws 99 threaded through the arms 98 are engageable with the outer face of the upper marginal portion of the casing 82. The screws 99 may be adjusted to rock the cover 95 about the tie bolt 94 as a pivot for determining the force with which the doctor blade is pressed against the transfer drum. It will be evident that the roller 87 rubs the cleaning fluid against the surface of the transfer drum, and that the doctor blade serves to scrape off the cleaning fluid and any ink which may be present on the surface of the transfer drum.

An important feature of the invention has to do with the means for driving the transfer drums and the cleaning units, as best seen in Figs. 4 and 5. One of the pivot studs 39 is extended and rotatably supports a combined gear and pulley unit 100. A gear element 101 of the unit 100 is driven by a gear 102 fast with impression cylinder 9. The impression cylinder 9, which is frictionally driven through the web by the associated engraving cylinder 10, serves through the gear 102 to drive the gear unit 100. A V-belt 103 runs upon the pulley portion 104 of unit 100, upon the pulley 91 of the cleaning unit 79, and upon a pulley 105 fast upon drive shaft 47 of transfer drum 8.

The belt and pulleys constitute a slip driving means for driving the transfer drum 8 from the impression cylinder 9 independently of the web but at substantially the speed at which the web travels. In order that the speed ratio may be adjusted, the V-pulley 105 is made to comprise relatively adjustable sections 106 and 107, a hub portion of the latter being extended through a hub portion of the former and fixed in adjusted position by a set screw 108. Turning the section 107 relative to the section 106 changes the effective width of the V-belt and the effective diameter of the pulley, thereby adjusting the drive ratio of the belt and pulley combination.

It is an important point that the pulley unit 100 is coaxial with the pivot studs 39, since this enables the swing frame to be swung about its pivot without affecting the operative adjustment of the belt and pulleys. It will be noted that the pulleys 100, 105 and 91 all rotate in the same direction, and that this is opposite to the direction of rotation of the impression cylinder. The arrangement is such that the transfer drum and the engaged impression cylinders are caused to travel at the same peripheral speed and without any dragging or rubbing.

A belt tensioning pulley 109 is rotatively carried by a pivoted arm 110 which is pivotally mounted upon a portion of the tie bolt 94 located outside the cleaning fluid reservoir. The arm 110 is provided with an arcuate slot 111 concentric with the tie bolt 94, and a headed clamping bolt 112 has its shank passed through the slot 111 and threaded into the end member 84 of the reservoir. The arm 110 may be clamped in any selected position of adjustment by the bolt 112 to cause the pulley 109 to apply any desired tension to the belt 103.

As has been mentioned, the drive of the impression cylinder is from the engraving cylinder. The engraving cylinders are all driven from a driving motor 121 which, through a sprocket 122 and a chain 123, drives a sprocket 124 fast on a horizontal shaft 125. The shaft 125, through

bevel gears 126 and 127, rotates a vertical drive shaft 128. From the vertical drive shaft 128 secondary or branch drive shafts 129 are driven (see Fig. 16) one for each engraving cylinder.

The shaft 129 is driven from the shaft 128 through bevel gears 130 and 131. The gear combination is enclosed in a casing 132, the gear 130 being supported in a ball bearing 133 and the gear 131 being supported in a ball bearing 134. The gear 131 is mounted upon a reduced end portion of the shaft 129, bearing through a washer 135 against a shoulder of the shaft 129. The gear 131 is keyed to the reduced end portion of the shaft 129 and is held in place against longitudinal movement by means of a washer 136 and a nut 137, the nut being threaded upon an extremity of the shaft. The shaft 129 extends through a casing 138, being mounted in the end of the casing remote from gear 131 in a ball bearing 139.

The shaft 129 has a key connection to a long spiral gear 140, the key connection forcing the gear 140 to turn in unison with the shaft 129, but permitting relative axial movement of the shaft 129 and the gear 140. The gear 140 is provided with thrust ball bearings 141 and 142 which are mounted at opposite sides of a plate 143. The plate 143 is attached by screws 144 to a broad toothed gear 145 which is normally stationary, but which is adapted to be rotatively driven through pinions 147 and 148 from a reversible electric running register adjusting motor 149 which is attached to the casing 138 exteriorly thereof. The gear 145 is threaded upon a sleeve 150 which has a flange portion, the sleeve being attached to the casing 132 by means of screws 151 which are passed through the sleeve flange and threaded into the casing 132.

When the motor 149 is operated, the gear 145 screws itself along the sleeve 150, and the spiral gear 140 and the gear 145 move longitudinally of the shaft 129 as a unit, the gear 140 not participating in the rotation of the gear 145 but continuing to be driven rotatively by the shaft 129. A reduced end portion of the gear 140 extends through the plate 143, supporting the ball bearings 141 and 142. A washer 152 impaled upon a further reduced extremity of the gear 140 is pressed against a shoulder and against the ball bearing 141 by a nut 153 which is threaded upon the extremity of the gear 140.

The driving spiral gear 140, which is rotatively driven by the shaft 129, transmits rotation to a driven spiral gear 154, normally fast with the engraving cylinder 8, through an intermediate spiral gear 155.

In normal running, the gear 145 does not turn so that the gears 140 and 145 remain in fixed position axially of the shaft 129, the gear 154 being driven in uniform relation to the drive shaft 129. When the running register motor is operated, the gear 145 rotates, shifting the gear 140 axially of the shaft 129 and thereby adjusting the phase relation of the gear 154 relative to the shaft 129. The capacity for running register adjustment is limited in extent by the available extent of axial movement of the gear 140 along the shaft 129. When this capacity is exhausted, however, a fresh capacity for running register adjustment may be provided by virtue of the novel transmission mechanism herein disclosed.

The intermediate spiral gear is rotatably mounted upon an eccentric 161 which is fast upon a shaft 162. The shaft 162 has fast with it

a crank handle 163 by which the shaft may be turned. The crank handle in the illustrative embodiment may be operated from the position illustrated in Fig. 16 in a counter-clockwise direction through a range of approximately 135°. Such rotation is not effective to disengage the teeth of gear 155 from the teeth of gear 140, but it is effective to disengage the teeth of gear 155 from the teeth of gear 154.

In the preliminary portion of the withdrawn movement of gear 155, the gear 154 is necessarily rotated slightly and causes the engraving cylinder to be rotated with it. When the gear 155 has been fully disengaged from the gear 154, the running register adjustment motor can be operated to shift the gear 140 axially of the shaft 129 with incidental rotation of the gear 155, but without rotation of the gear 154. By operating the gear 140 exactly a whole number of tooth spaces longitudinally of the shaft 129, the gear 155 will be caused to turn exactly a whole number of tooth spaces, so that when it is restored to driving engagement with the gear 154, with the crank handle 16 returned to the position of Fig. 16, the gear 154, as an incident of such restoration, will be turned slightly to return the engraving cylinder to exactly its original position. Thus the provision of a fresh capacity for running register adjustment may be made quickly and without in any way disturbing the phase relation of the engraving cylinder 8 to the shafts 128 and 129 and to the other engraving cylinders of the machine.

The gear 155 is mounted in a housing 164, through which the shaft 162 extends. The crank 163 is provided with a plunger type handle 165, the plunger including a pin 166 which is adapted to fit into a recess of the casing 164 to detain the handle in the position illustrated in Fig. 16.

The mounting of the gear 155 with capability for movement between engaged and disengaged positions is also advantageous in connection with the introduction of the engraving cylinder into operative position and with withdrawal therefrom.

The frame members 13 and 14 are provided with cup-like bosses 171 and 172, respectively. The engraving cylinder 8 is made fast upon an engraving cylinder shaft 173 which extends through the frame members 13 and 14 and which are mounted in bearing units 174 and 175, the former being secured to the frame member 13 by screws 176, and the latter to the frame member 14 by screws 177.

The bearing unit 174 comprises a sleeve member 178 which, between plates 179 and 180, carries a roller bearing 181 in which one end of the shaft 173 is revolvably mounted. The right-hand extremity of the shaft 173, as viewed in Fig. 10, is formed as a threaded extension 182. A threaded plug member 183 is screwed into the casing 171. The plug member carries a ball bearing 184 which is held in place between the plate 185 affixed to the plug 183 and a plate 186 which is adapted to be passed loosely over the threaded end portion 182 of the shaft 173. A nut 187 threaded on 182 fixes the position of the plug 183, engages the plate 186 and fixes the position of the plug 183 relative to the shaft 173. The plug 183 is provided with a hand wheel 188 so that the plug may be rotated to adjust its position in the bearing unit 174 in the direction of the axis of the shaft 173. Such adjustment shifts the shaft 173 axially and adjusts the engraving cylinder 8 along with the shaft, so that lateral registration

11

of the several color designs can be obtained by axial adjustment of the plugs 183 of the several engraving cylinders.

When it is desired to withdraw the engraving cylinder 8 from the machine, it is necessary first to withdraw the bearing unit 174 from engagement with the shaft 173. This is accomplished by unscrewing the screws 176 and detaching the nut 187. The unit 174 is then withdrawn axially of the shaft 173 leaving the shaft 173 free, so far as that bearing unit is concerned, to be rolled along a horizontal shelf or ledge 189 to roll the shaft and the cylinder 8 out of the machine. When the unit 174 is withdrawn, the plate 186 and the ball bearing 184 remain in place in the unit, the plate 186 being trapped by an inwardly extending flange 189 of the plug 183.

The bearing unit 175 at the left-hand end of the shaft 173, as viewed in Fig. 10, comprises a casing or sleeve member 190. A roller bearing 191 is carried in the sleeve between plates 192 and 193. The spiral gear 154 is carried by the sleeve 190, being keyed to the shaft 173 to drive the shaft rotatively while permitting the shaft to be adjusted longitudinally relative to the gear by operation of the plug 183. The gear 154 runs in ball bearings 195 and 196.

A cap member 197 having handles 198 is detachably secured to the open end of the sleeve 190 by screws 199. The cap member 197 is provided with slotted ears 200, the slots 201 of which are adapted to receive the shanks of the screws 199 when the screws are partially backed out. When the cap member is placed on the end of the shaft 173, and then against the end of the sleeve 190, it can be attached through the ears 200 and the screws 197 to the sleeve 190 by a turning movement of only a few degrees. The screws 199 are then tightened to clamp the cap member firmly in place. The cap 197 normally forms a fixed part of the bearing unit 175, so that the handles 198 may be utilized for withdrawing the entire unit 175 lengthwise of the shaft 173 when the screws 177 have been withdrawn.

When the bearing units 174 and 175 have been withdrawn, the shaft 173 rests upon a horizontal shelf or ledge 202 of the frame member 14 and upon the horizontal shelf or ledge 189, so that the shaft, together with the engraving cylinder 8 supported by it, may be rolled along the shelves 189 and 202 and out of the machine.

It will be observed that because the gears 154 and 155 are spiral gears, the bearing unit 175 cannot be withdrawn axially of the shaft 173 without producing incidental rotation of the shaft so long as the gear 155 is engaged with the gear 154. By first shifting the gear 155 to its disengaged position, however, the gear 154 is freed and the unit 175 may be withdrawn without producing any tendency to rotate the shaft 173.

Attention has previously been called to the fact that there is but one position in which the axis of the shaft 173 may be mounted, notwithstanding the fact that the engraving cylinders 8 for different jobs are of different diameters. It is important, therefore, that provision be made for mounting an ink reservoir unit in different operative positions for cooperation with engraving cylinders of different diameters.

It is a desirable and advantageous feature of the present invention not only that provision be made for mounting the ink reservoir in different operative positions, but also that provision be made for oscillating the ink reservoir unit in its

entirety lengthwise of the printing cylinder 10. These requirements for adjustable mounting and for oscillation introduce problems in connection with the sealing of the ink reservoir, the driving of the ink applying roller 16 in different positions of adjustment, and the driving of the ink applying roller 16 notwithstanding that it participates in the oscillation of the ink reservoir unit.

The ink reservoir unit in its entirety is supported upon a track 211 which extends between the frame members 13 and 14. The ink reservoir unit is adapted to be mounted upon a base member 212 which interfits with the track 211 and is supported upon the track for sliding movement in the direction of the axis of the engraving cylinder 10. Base member 212 comprises a plate 213 and a guide bar 214 which is secured to the plate by screws 215.

A lint blade carrier 216 is pivotally mounted on the base 212 and supports a lint blade 217 in engagement with the engraving cylinder. An adjusting screw 218 is threaded through a flange 219 of the supporting track 211 to engage a tail portion of the lint blade carrier 216. The screw also extends through a flange 220 of the track 211 and is provided with an operating knob or head 221 conveniently accessible to the operator. The lint blade 217 may be adjusted to bear with desired pressure against the engraving cylinder, regardless of variations of diameter of the engraving cylinder, by adjustment of the screw 218. It will be observed that the lint blade, because it is mounted upon the sliding base 213, participates in the oscillation of the base 213.

The base 213 is formed with ribs 222 which extend toward and from the engraving cylinder. Opposed to each rib 222 is a guide bar 223 which is secured to the base 213 by screws 224. Between each rib 222 and associated guide bar 223 a block 225 is slidably mounted, the blocks 225 serving as supports for direct engagement with and attachment to flanges 226 of the ink reservoir 227. The reservoir 227 is attached through bolts 228 to the blocks 225, but the blocks 225 are capable of adjustment along their guide-ways for determining the position of the reservoir and the mechanism carried by it, so that the reservoir and such mechanism may properly cooperate with engraving cylinders of different diameters. Screws 229 threaded through brackets 230 attached to the base 213 engage the outer ends of the blocks 225 and may be adjusted by turning to press the blocks toward the engraving cylinder.

When the engraving cylinder is to be replaced by a cylinder of larger diameter, the screws 229 are desirably backed out far enough so that the ink reservoir may be put in place and attached upon the blocks 225 without engaging the ink applying roller with the new engraving cylinder. When the new engraving cylinder has been put in place and the ink reservoir has been attached to the blocks 225, the screws 229 are then operated to move the blocks and the supported reservoir toward the engraving cylinder until such movement is arrested by engagement of the ink applying roller 16 with the engraving cylinder 10.

The ink reservoir is equipped with a flexible sealing blade 231 which is held in place by a clamp bar 232 and by screws 233 which are passed through the clamp bar 232 and through slots in the sealing blade for holding the sealing blade 231 in different adjusting positions. Because of the flexibility of the sealing blade and its capacity for adjustment, the sealing blade

may be made to run in engagement with engraving cylinders of different diameters notwithstanding the adjustment of the reservoir unit to cause the ink applying roller 16 to run in engagement with the various engraving cylinders.

The ink reservoir is also provided with a doctor blade 234 for scraping off surplus ink from the engraving cylinder, the doctor blade also serving the function of a sealing blade. The reservoir has attached to it by screws 235 a closure plate 236 upon which there is mounted a further plate 237. A clamping plate 238 attached to the plate 237 cooperates with the latter plate for clamping in place a spring blade which bears against the under surface of the doctor blade 234 to stiffen the doctor blade. A biasing plate 239 is provided with an outer downwardly extending marginal flange through which it rests upon the plate 238 and with an inner downwardly extending marginal flange which rests upon the doctor blade.

The biasing plate may be pressed downward with nicely adjusted pressure to determine the force with which the doctor blade presses against the engraving cylinder. For this purpose a lever 240 is provided, the lever including an outwardly extending tail portion 241 and inwardly extending arms 242. The lever 240 is rockably supported upon a shaft 243 mounted in bearings 244 which are affixed to the end walls of the reservoir 227. Each of the arms 242 has threaded through it a pressure adjusting screw 245 which bears against the biasing plate 239, the screws being provided so that the pressure exerted against the plate 239 may be evenly distributed throughout the length of the plate 239. Each screw 245 is provided with a lock nut 246. Besides the distributional adjustment provided by the screws 245, provision is made for adjusting the lever 240 as a unit. A screw 247 having a knurled head is threaded through an ear 249 of the reservoir 227 and bears upwardly against the under face of the tail 241 of the lever 240. With the arrangement described, the doctor blade can be adjusted to bear with desired pressure against engraving cylinders of different diameters.

The portion of the lever 240 which surrounds the shafts 243 is made in the form of a complete cylinder 250 in order that it may contribute to the closing of the top of the ink reservoir. At the outer side of the cylinder 250 a cover plate 251 having an upturned lip 252 for engaging the cylinder 250 is affixed to the reservoir 227 by means of screws 253. The cover 250 is provided with a filling opening 254 which is normally closed by a cap 255. The cap 255 is pivotally secured to the cover 251 by means of a rivet 256. The cover 251, together with the cylinder 250 and the doctor blade mechanism, forms a complete cover for the reservoir 227 which sealingly engages through the doctor blade the engraving cylinder 10. The doctor blade 234 and the sealing blade 231 extend the full length of the reservoir 227 and have straight ends.

For the purpose of completing the sealed relation of the reservoir 227 to the engraving cylinder 10, and this notwithstanding the fact that the engraving cylinders employed may vary in diameter, the end walls of the reservoir 227 are formed with seal engaging and fitting seats 261. End seals 262, desirably of fiber, are provided, and are attached in fitting relation to the seats by screws 263. Each end seal is formed with a concave face 264 adapted to fit in sealing engagement

against the periphery of an engraving cylinder of selected diameter. The end seals also extend across the ends of the doctor blade and the sealing blade in sealing engagement with the ends of the blades. Thus, the closure of the reservoir is complete so that volatile, quick drying solvents or vehicles for the ink may be employed if desired.

When the engraving cylinders are replaced by 10 engraving cylinders of a different diameter, the end seals are also replaced by fresh end seals whose concave faces 264 are of the same radius of curvature as the replacement cylinders. This 15 substitution of end seals can be very readily effected, simply by withdrawal of the screws 263 and reapplication of the screws after the end seal substitution has been made.

The ink applying roller 16 is revolvably mounted in the end walls of the reservoir 227, and since 20 it would not be desirable to have the roller 16 oscillate with relation to the reservoir 227 it is mounted to participate in the oscillation of the reservoir.

The means for oscillating the reservoir and 25 for driving the roller 16 are driven from the secondary driving shaft 129 of the particular printing unit. As seen in Fig. 16, a reduced portion of the shaft 129 extends beyond the casing sleeve 138 and into a casing 271, being supported in 30 ball bearings 272 and 273. The shaft 129 has affixed to it a worm 274 which drives a worm wheel 275 fast on a shaft 276. The shaft 276 has fast upon it a peripheral track cam 278, the 35 track of which receives a pin 279 affixed to an ear 280 of the base 213. The cam 278 is thus caused to impart to the base 213 one complete oscillation for each revolution of the shaft 276.

The shaft 276 also has fast upon it a straight gear 281 through which the ink applying roller 16 is driven. The gear 281 drives a gear 282 which is revolvably mounted upon a stationary shaft 283. An arm 284 is pivotally mounted upon the shaft 283, and revolvably supports a gear 285 in mesh with the gear 282. The gear 285 is a 45 broad toothed gear which engages a gear 286 fast upon the shaft 287 of the ink applying roller 16. The arm 284 may be swung about the axis of shaft 283 without affecting the driving engagement of gear 285 with gear 282. Thus, the 50 gear 285 may be swung into driving engagement with the gear 286 to provide a complete driving train to the gear 286 regardless of the position in which the gear 286 is maintained for cooperation with the engraving cylinder 10. Suitable 55 means are provided for fixing the arm 284 in any position to which it may be adjusted, as, for example, by providing the arm with a slit tail 288 the portions of which are connected through a clamping screw 289 for clamping the arm in 60 adjusted position upon the stationary shaft 283.

The broad teeth of gear 285 enable driving engagement to be maintained between the gears 285 and 286 even though the gear 285 occupies a fixed axial position, while the gear 286 oscillates with the unit 16.

While the printing web has been shown and described as passing directly from the last impression cylinder 9b, against which printing is done, to the roller 11, it is pointed out that if the 70 number of colors to be applied is less than the total number of printing units provided in the machine, the web may advantageously be threaded through an idle unit following the last one which does any printing, the last unit being 75 simply provided with an empty ink reservoir, or

15

having its reservoir left out of the machine. Thus, if colors were applied only by the engraving cylinders 10 and 10a of the illustrative machine, the web might, nevertheless, be passed around transfer drum 8b and impression cylinder 9b to provide the added protection against application of undesired tension to the web at the last printing operation which would be afforded by the elements 8b and 9b.

I have described what I believe to be the best embodiments of my invention. I do not wish, however, to be confined to the embodiments shown, but what I desire to cover by Letters Patent is set forth in the appended claims.

What I claim is:

1. In a multi-color web printing press which comprises a plurality of printing couples each including a printing cylinder and an impression cylinder, and a web transfer drum adapted to bear against each of a pair of successive impression cylinders, in combination, a carrier for one of the impression cylinders operable to carry the impression cylinder bodily toward and from the cooperative printing cylinder, means supporting an associated web transfer drum from said carrier for movement in unison with the said impression cylinder toward and from operative position, for movement toward and from said impression cylinder, and for movement toward and from a neighboring cylinder parallel to said impression cylinder, and means for adjusting the relation of the transfer drum relative to said impression cylinder and to the neighboring parallel cylinder.

2. In a multi-color web printing press which comprises a series of printing couples each including a printing cylinder and an impression cylinder, and web transfer drums arranged in alternation with the impression cylinders and adapted to bear against adjacent impression cylinders, in combination, carries for the respective impression cylinders each operable to carry its impression cylinder bodily toward and from the cooperative printing cylinder, means on each carrier supporting one of the web transfer drums in bearing relation to the impression cylinder carried by such carrier for movement toward and from operative position in unison with the impression cylinder mounted on said carrier, and for movement relative to the carrier toward and from a neighboring parallel cylinder, and means for adjusting the relation of the transfer drum to the neighboring parallel cylinder.

3. The combination set forth in claim 2 in which each carrier comprises a pair of slides in which the opposite ends of the impression cylinder are rotatably mounted, and which further includes a common driving member for said slides and parallel driving connections between the driving member and the slides.

4. In a multi-color web printing press which comprises a plurality of printing couples each including a printing cylinder and an impression cylinder, and a web transfer drum adapted to bear against each of a pair of successive impression cylinders, in combination, a carrier for one of the impression cylinders operable to carry the impression cylinder toward and from the cooperative printing cylinder, a swing frame pivotally mounted on the carrier and supporting said web transfer drum for movement with the impression cylinder mounted on the carrier, slide bearings for the web transfer drum mounted in the swing frame, adjustable spring means for urging the bearings toward the impression cyl-

5

inder mounted on the carrier, and adjustable spring means for yieldingly urging the swing frame about its pivot to press the web transfer drum against a neighboring impression cylinder.

5. In a multi-color web printing press which comprises a series of printing couples each including a printing cylinder and an impression cylinder, and web transfer drums arranged in alternation with the impression cylinders and adapted to bear against adjacent impression cylinders, in combination, carriers for the respective impression cylinders each operable to carry its impression cylinder toward and from the cooperative cylinder, a swing frame pivoted

10 on each carrier and supporting one of the web transfer drums for movement toward and from operative position with the carrier, slide bearings for the web transfer drum mounted in the swing frame, adjustable spring means for urging the bearings toward the impression cylinder mounted on the carrier, adjustable spring means for yieldingly urging the swing frame about its pivot, and means for locking the swing frame rigidly against pivotal movement.

15 20 25 30 35 40 45 50 55 60 65 70 75 80 85 90 95

6. In a multi-color web printing press, in combination, a pair of slides adapted revolvably to support the opposite ends of an impression cylinder, guide means for guiding the slides between operative and retracted positions, means for operating the slides in unison along the guides, a swing frame pivoted on the slides, a web transfer drum supported on the swing frame, slideable bearings for the web transfer drum mounted on the swing frame, guides on the swing frame for the slideable bearings, adjustable spring means for yieldingly urging the slideable bearings along the swing frame guides, adjustable spring means for yieldingly urging the swing frame about its pivot, means for locking the slideable bearings rigidly to the swing frame, and means for positively limiting pivotal movement of the swing frame under the influence of the last mentioned spring means.

7. In a multi-color web printing press which 43 48 53 58 63 68 73 78 83 88 93 98 comprises a plurality of printing couples each including a printing cylinder and an impression cylinder, and web transfer drums arranged in alternation with the impression cylinders and arranged to bear through the web with driving pressure against adjacent impression cylinders, in combination, a carrier common to one of the impression cylinders and an associated web transfer drum for shifting said impression cylinder and drum together between operative and retracted positions, said impression cylinder tending frictionally to drive the drum through the web, and driving means forming an independent frictional slip drive from the impression cylinder to the drum for assisting in driving the drum from the impression cylinder.

8. In a multi-color web printing press which 43 48 53 58 63 68 73 78 83 88 93 98 comprises a plurality of printing couples each including a printing cylinder and an impression cylinder, and web transfer drums arranged in alternation with the impression cylinders and adapted to bear against adjacent impression cylinders, in combination, a carrier common to one of the impression cylinders and an associated web transfer drum for shifting said cylinder and drum together between operative and retracted positions, said cylinder tending frictionally to drive the drum through the web, and means forming an independent frictional slip drive from the impression cylinder to the drum for assisting in driving the drum from the impression cylinder,

16

said frictional slip drive comprising a V-belt and a plurality of V-pulleys upon which the belt runs, and means for adjusting the width of at least one of the pulleys to adjust the drive ratio of the slip drive.

9. In a multi-color web printing press which comprises a plurality of printing couples each including a printing cylinder and an impression cylinder, and web transfer drums arranged in alternation with the impression cylinders and adapted to bear against adjacent impression cylinders, in combination, a carrier common to one of the impression cylinders and an associated web transfer drum for shifting said cylinder and drum together between operative and retracted positions, said cylinder tending frictionally to drive the drum through the web, and means forming an independent frictional slip drive from the impression cylinder to the drum for assisting in driving the drum from the impression cylinder, said frictional slip drive comprising a V-belt and a plurality of V-pulleys upon which the belt runs, and means for adjusting the width of at least one of the pulleys to adjust the drive ratio of the slip drive, a cleaner carried with the web transfer drum and comprising a solvent applying roller and a doctor blade engageable with the drum, and means operated by the slip drive for operating the solvent applying roller in rubbing relation to the drum.

10. In a multi-color web printing press which comprises a series of printing couples each including a printing cylinder and an impression cylinder, and web transfer drums arranged in alternation with the impression cylinders and adapted to bear against adjacent impression cylinders, in combination, carriers for the respective impression cylinders each operable to carry its impression cylinder toward and from the cooperative printing cylinder, a swing frame pivoted on each carrier and supporting one of the web transfer drums for movement toward and from operative position with the carrier, slide bearings for the web transfer drum mounted in the swing frame, adjustable spring means for urging the bearings toward the impression cylinder mounted on the carrier, adjustable spring means for yieldingly urging the swing frame about its pivot, said impression cylinders tending frictionally to drive the web transfer drum through the web, and means forming an independent slip drive from one of the cylinders to the drum carried in common with such cylinder for assisting in driving the drum, said slip drive comprising pulleys which are coaxial, respectively, with the drum and with the swing frame, and a friction belt running on said pulleys, a cleaner mounted on the swing frame for cleaning the web transfer drum comprising a solvent reservoir, a solvent applying roller and a doctor blade, and means for driving the solvent applying roller comprising a pulley fast with said roller upon which the friction belt is trained.

11. In a multi-color web printing press which comprises a series of printing couples each including a printing cylinder and an impression cylinder, and web transfer drums arranged in alternation with the impression cylinders and adapted to bear against adjacent impression cylinders, in combination, carriers for the respective impression cylinders each operable to carry its impression cylinder toward and from the cooperative cylinder, a swing frame pivoted on each carrier and supporting one of the web transfer drums for movement toward and from operative position with the carrier, slide bearings for the web transfer drum mounted in the swing frame, adjustable spring means for urging the bearings toward the impression cylinder mounted on the carrier, adjustable spring means for yieldingly urging the swing frame about its pivot, said impression cylinders tending frictionally to drive the web transfer drum through the web, and means forming an independent slip drive from one of the cylinders to the drum carried in common with such cylinder for assisting in driving the drum, said slip drive comprising pulleys which are coaxial, respectively, with the drum and with the swing frame, and a friction belt running on said pulleys, a cleaner mounted on the swing frame for cleaning the web transfer drum comprising a solvent reservoir, a solvent applying roller and a doctor blade, and means for driving the solvent applying roller comprising a pulley fast with said roller upon which the friction belt is trained.
